CLAIM

I claim the ornamental design for an automotive vehicle wheel, as shown and described.

DESCRIPTION

FIG. 1 is a top perspective view showing my new design for an automotive vehicle wheel;

FIG. 2 is a side plan view thereof;

FIG. 3 is a top plan view thereof;

FIG. 4 is a rear plan view thereof;

FIG. 5 is a bottom plan view thereof;

FIG. 6 is a front plan view thereof; and,

FIG. 7 is a side plan view thereof, opposite FIG. 2.

The broken lines illustrate portions of the automotive vehicle wheel that form no part of the claimed design. The stippling pattern indicates a contrast in appearance.
